UNITED STATES PATENT OFFICE.

ALANSON H. MERRIMAN, OF MERIDEN, CONNECTICUT.

POWER-PRESS.

SPECIFICATION forming part of Letters Patent No. 316,989, dated May 5, 1885.

Application filed January 29, 1885. (No model.)

To all whom it may concern:

Be it known that I, ALANSON H. MERRIMAN, a citizen of the United States, residing at Meriden, in the county of New Haven and State of Connecticut, have invented certain improvements in Power-Presses, of which the following is a specification.

My improvements relate to the mechanism for connecting and disconnecting the driving-wheel with the press-shaft.

In the accompanying drawings, Figure 1 is a side elevation, partly in vertical section on line $x x$ of Fig. 2, of so much of a power-press as is necessary to illustrate my improvement. Fig. 2 is a vertical section of the same, partly in elevation, the plane of section being indicated by line $y y$ of Fig. 1; and Fig. 3 is a side elevation of that side of the wheel which faces the press-frame, together with a transverse section of the press-shaft.

A designates a portion of the frame of a press, and B the main shaft, which is supported by said frame in any suitable bearings. This shaft is provided with an enlarged portion in the form of a collar, a , and by the side of this collar the driving-wheel C is mounted loosely upon said shaft. For convenience I have only illustrated the hub of this wheel.

A strike pin or dog, b , is firmly secured to the press-shaft in any proper manner, but preferably by a screw-thread, as shown. The side of the wheel-hub C is provided with a recess, c , which covers the strike pin or dog b .

At one side of the recess c , I form a radial groove in the hub of the wheel, within which I place the sliding clutch-bolt D. This bolt is held in place by means of a cap, d , and is provided with suitable stops for limiting the range of its longitudinal movement—as, for instance, the stop-pin f , which lies within a slot in the cap-plate d . I also provide some friction device to prevent an accidental movement of the clutch-bolt D—as, for instance, a spiral spring, g , Fig. 2—one end of which bears continually against one side of the clutch-bolt. In the outer end of the clutch-bolt I form a transverse slot, (shown most at h , Fig. 3,) the side walls of which slot form two opposing shoulders.

Upon the frame of the press I arrange a sliding shipper, E, which may be supported so as to slide radially to and from the wheel-

hub. As illustrated, this movement is vertical. This shipper may be guided in its longitudinal movement by any suitable ways or guides, 55 and is designed to be forced in one direction—as, for instance, downward—by means of a suitable spring, and in the opposite direction by means of a treadle, which it is deemed unnecessary to illustrate.

Upon the upper end of the sliding shipper, and projecting sidewise toward the path of the clutch-pin, is a cross-arm, k , the upper side of which is straight and square across, and the under side of which is beveled in opposite directions, as shown in Fig. 1. The height of this cross-arm at its deepest place is such as will just about fill the transverse slot in the clutch-bolt.

When the driving-wheel and press-shaft are disconnected, the clutch-bolt will be held outward, as illustrated by the broken lines at the right of Fig. 1, and the sliding shipper will be held downward with its cross-arm in the position indicated by the broken lines in said figure. When in this position, the driving-wheel may revolve continuously without changing the position of the clutch-bolt. By throwing the shipper-slide upward into the position indicated by full lines in Fig. 1, the inner wall 70 of the slot in the clutch-bolt, moving in the path indicated by the broken line n , will engage with the upper face of the cross-arm k , and force the clutch-pin from the position indicated by broken lines into that indicated 75 by full lines in Fig. 1, so that the inner end of the clutch-bolt will engage the strike pin or dog b , and thereby necessitate the movement of the press-shaft with the driving-wheel so long as the sliding shipper remains elevated. 80 When the sliding shipper is brought downward again, the outer wall of the slot through the clutch-bolt D, moving in the path indicated by the broken lines m , will engage the under side of the cross-arm k , and thereby withdraw the clutch-bolt from engagement 85 with the strike pin or dog. 90

It should be noticed that by making a bevel upon each side of the cross-arm k the clutch-bolt is operated the same when the driving-wheel is moved in either direction.

I claim as my invention—

1. In a power-press, the driving-wheel having the clutch-bolt D fitted to move radially

within its hub, substantially as described, and for the purpose specified.

2. The combination of the press-shaft having the strike pin or dog *b*, the driving-wheel *C*, loosely mounted upon said shaft, the clutch-bolt *D*, fitted to move radially within the hub of said wheel, and having at its outer end two opposing shoulders, as the walls of the slot *h*,

and the sliding shipper having a straight and an inclined face for acting upon the opposing shoulders of the clutch-bolt, substantially as described, and for the purpose specified.

ALANSON H. MERRIMAN.
